UNITED STATES PATENT OFFICE.

CHARLES F. MURRAY, OF EVANSTON, ILLINOIS, ASSIGNOR TO THE FOWLER CAR COMPANY, OF CHICAGO, ILLINOIS, A CORPORATION OF ILLINOIS.

CAR SIDE.

1,093,876.

Specification of Letters Patent. Patented Apr. 21, 1914.

Application filed September 29, 1913. Serial No. 792,250.

To all whom it may concern:

Be it known that I, CHARLES F. MURRAY, a citizen of the United States, and resident of Evanston, in the county of Cook and 5 State of Illinois, have invented certain new and useful Improvements in Car Sides, of which the following is a specification.

My invention relates to railway cars and has particular reference to a novel side construction for single sheathed steel frame 10 cars.

In the construction of single sheathed box cars, the sheathing being disposed interiorly of a steel frame and extending longitudinally 15 of the car, it has heretofore been customary to bolt the individual planks to the metallic frame posts. This necessarily involved the punching of a multitude of holes in the frame thus materially weakening the 20 same; also the boring of an equal number of holes in the side planking. The provision of such holes provided access for moisture and the deterioration of the side planks frequently began at the point of the passage 25 of bolts through the sheathing.

The present invention has for its object the provision of means whereby the sheathing may be held in proper position against the frame posts without the use of a large 30 number of bolts and therefore without weakening the frame by punching. In addition the saving in labor cost is material.

In my construction I provide a plurality of rigid posts disposed interiorly of the sheathing flush with the surface thereof and removably secured to the frame posts in such manner that the posts may be removed in order to replace broken side planks as required.

It has been found desirable to provide 40 means for tightening the side planks one upon the other, to take up shrinkage and warping. Obviously this may be done in a number of ways, several of which are illustrated in the present application. In all 45 the forms illustrated the tightening force is exerted between the top side plate and the top of the sheathing.

The invention will be more readily understood by reference to the accompanying 50 drawings, wherein,

Figure 1 is a transverse vertical section through a railway car constructed in accordance with my invention; Fig. 2 is an inside elevation of the construction shown in

Fig. 1; Fig. 3 is a fragmentary elevation 55 of the top portion of the construction shown in Figs. 1 and 2, with a simple wedge in place. Fig. 4 is a section on the line 4-4 of Fig. 3; Fig. 5 is a transverse vertical section through a box car showing a modified form of securing means for the inside post; Fig. 6 is an inside elevation of the construction shown in Fig. 5; Fig. 7 is a fragmentary sectional view on the line 7-7 of Fig. 6; Fig. 8 is a section on the line 8-8 65 of Fig. 5; and Fig. 9 is a side elevation of a car constructed in accordance with my invention.

Referring more particularly to the drawings it will be seen that a car constructed in 70 accordance with my invention may have a side sill 10, a Z-bar top plate 11, and vertical frame posts 12.

Interiorly of the frame the sheathing 13, is placed, the boards extending longitudinally 75 of the car. As a means for maintaining the sheathing in place I provide angular, preferably channel-shaped posts 14, extending from top to bottom of the sheathing on the inside of the car the posts being 80 gained into the boards to provide a flush inner surface. At the top the posts 14 are spaced away from the side plate 11, by means of a filler 15, and held in place by a bolt 16, passing through the web of the 85 channel 14, and through the web of the side plate 11. At the bottom a round bar 17, having a flattened end is riveted to the web of the channel 14, the round end of the rod extending down through the floor and 90 through a flange of the side sill 10. By this means the post and sheathing are restrained from lateral movement the sheathing being securely maintained in position.

A slightly modified construction is shown 95 in Figs. 5 and 6, wherein the post 18 has a hooked upper end 19, adapted to engage one leg of the side plate 11. A bolt 20 securely holds the post against the side plate. At the bottom the post 18 is secured by means of 100 a bolt 21, to a vertical frame post 12, the inside post 18 not passing downward through the side sill.

As a means for tightening the planking upon each other, I may provide a simple 105 wedge such as shown in Fig. 3, in which one of the members 22 is riveted to the side plate 11, the other member 23, of the wedge be-

ing a temporary affair which may be either of wood or metal. In Figs. 1 and 2 a more elaborate wedge construction is shown, wherein in the lower wedge member 23^a is held against 5 longitudinal movement, the upper wedge member 24, being brought into co-operation therewith by means of a bolt 25, having a bearing on an angle 26, riveted to the side plate.

10 In Figs. 6 and 7 a modified form of tightening means is shown, wherein a metal plate 27, is seated in the top plank and provides a bearing for a nut 28, threaded on a bolt 29, the head of which bears against the inner leg 15 of the top plate 11.

Other forms of tightening means may be employed and other modifications may be made in the structure shown, all without departing from the spirit of my invention.

20 I claim:

1. In a railway box car, the combination of metallic frame posts, a single, interior, sheathing, said sheathing extending from door to end posts on the sides, and interior 25 posts extending from top to bottom of the car, said posts having a rigid but removable connection to the car frame at the top and bottom of said posts, said posts acting as the sole means for maintaining said sheathing 30 in proper relation to said frame, substantially as described.

2. In a railway box car, the combination of metallic frame members, a single, interior, sheathing, said sheathing extending from 35 door to end posts on the sides, a plurality of flanged posts located interiorly of the car and acting as the holding means for maintaining said sheathing in position on said frame, said posts having a rigid but removable connection to the frame members at the 40

top and bottom of the car, substantially as described.

3. In a railway box car, the combination of metallic frame members, a single, interior, sheathing, said sheathing extending from 45 door to end posts on the sides, a plurality of channel-shaped posts located interiorly of the car with their surfaces flush with the surface of said sheathing, said posts having a vertically immovable bolt connection to 50 said frame members at the top and bottom of the car, substantially as described.

4. In a railway box car, the combination of metallic frame members, a single, interior, sheathing, said sheathing extending from 55 door to end posts on the sides, sheathing retaining posts located interiorly of the car with their surfaces flush with the surface of said sheathing, a rigid but removable connection between said interior posts and said 60 frame members at the top and bottom of the posts, and means for exerting tightening force on said sheathing, said force acting between an upper frame member and the top of said sheathing, substantially as described. 65

5. In a railway box car, the combination of metallic frame members, a single, interior, sheathing, said sheathing extending from door to end posts on the sides, sheathing retaining posts located interiorly of the car 70 with their surfaces flush with the surface of said sheathing, a rigid but removable connection between said interior posts and said frame members at the top and bottom of the posts, and wedge means for tightening said 75 sheathing, substantially as described.

CHARLES F. MURRAY.
